UNITED STATES PATENT OFFICE.

JULIA H. AUERBACH, OF LOS ANGELES, CALIFORNIA.

DETACHABLE SELF-ADJUSTING CORSET-STRAP.

1,271,259.

Specification of Letters Patent.

Patented July 2, 1918.

Application filed November 5, 1915. Serial No. 59,732.

To all whom it may concern:

Be it known that I, JULIA H. AUERBACH, a citizen of the United States, and resident of the city of Los Angeles, in the county of 5 Los Angeles and State of California, have invented certain new and useful Detachable Self-Adjusting Corset-Straps, of which the following is a specification.

My invention relates to improvements in 10 detachable self adjusting corset straps, and the object of my invention is to provide a simple and convenient self adjusting device for tightening a corset or the like.

My invention is illustrated in the accompanying drawings, in which—

Figure 1 is a view of the preferred form of my device,

Fig. 2 is an optional form of the same.

Fig. 3 is a section of the device, on the 20 line 3—3 in Fig. 1,

Fig. 4 is a section of the optional form of the device on the line 4—4 in Fig. 2.

Fig. 5 is a view of an optional form of the back lacing of the corset by the use of 25 my device, and

Fig. 6 is a view of the lacing plate.

Similar characters refer to similar parts throughout the several views.

My device comprises a plate 1 having 30 apertures 2, formed in its inner marginal edge section, a buckle or clasp 3, adjacent each of said apertures 2, and a plurality of bent over hook sections 4, 4, 4 and a ribbon 5 of suitable fabric, carrying lacing plates 6 and 7. The ribbon 5 is threaded through 35 a buckle or clasp 3 and is thence carried over the plate 1, and turned back and passed upward through the apertures 2 in the plate 1 and carried back to the lacing plate 6

40 through which it is threaded, and thence carried back to the plate 1 where it is passed downwardly through the apertures 2 in the inner marginal section thereof and carried thence back through the lacing plate 7 from

45 which it is again brought forward to the plate 1 and passed again through the buckle or clasp 3 whereby the two end sections of the ribbon 5 will be held together securely by means of the buckle or clasp 3, while the 50 loops of the ribbon 5 carrying the lacing plates 6 and 7 will be free to adjust their relative positions by means of the free loop of the ribbon 5 in the aperture or slot 2.

In use the hook sections 4, 4 of the plate 1

are caught over or hooked upon the front 55 margin of a corset or the like of any desired style and the hooks 8 and 9 carried by the lacing plates 6 and 7 respectively are inserted in eyelets 10 in the marginal back strip of a corset 11.

The device is intended to be used in pairs, one member of the pair being provided on each side of the corset, and the members of the pair are counterparts, but, if desired, one of the members of the pair may be provided with a front plate 12 provided with a slot 13 and eyelets 14, 14 adapted to be placed over studs provided on the usual form of corset and a marginal bar 15 may be provided on the plate 12 to receive the 60 hooks 4, 4, of the plate 1.

In the optional form of the device illustrated in Fig. 2, the loop of the ribbon 5 intermediate its end loops 5' and 5'' is carried back to a plate 16 intermediate the front and back of the corset sections and the intermediate loop of the ribbon 5 is passed through a slot 17 in the plate 16. In this form of the device the lacing plates 19 are carried by the loops 5' and 5'' as above described. In this form of the device the intermediate plate 16 is provided with a buckle 18 which engages the ribbon 5 to hold the plate 16 in the desired position, and the ends of the ribbon 5 are secured by the buckle 3 75 on the plate 1 as above described. The lacing plates 19 are preferably provided with hooks 20, 20 adapted to engage the eyelets of the usual form of corset but any desired form of engaging means may be used as desired. The lacing plate 19 is provided with a slot 21 through which the ribbon 5 is 80 threaded.

In the optional form of lacing illustrated in Fig. 5, the ribbon 5 is carried across the 95 back of the corset from side to side through the lacing plates 19, 19 and thence secured in front by means of the buckle 3.

As many pairs of my device may be used upon a corset as desired and it may be substituted for the ordinary and usual form of lacing or it may be used in conjunction with the usual form of lacing if desired and it is also adapted for use as an abdominal support.

My device is adapted to be used either under or over a corset or the like of any desired style and with it the corset may be

easily and conveniently adjusted to the body without the usual form of lacing and it may also be readily removed when desired.

Having thus described my invention, what I claim is:

1. In a device of the character described, a plate adapted to engage a corset, a plurality of hooks adapted to engage a corset, and a strap section engaging the plate and independently engaging the hooks.

2. In a device of the character described, a plate adapted to engage a corset, a plurality of hooks adapted to engage a corset, and a strap section engaging the plate and formed as a loop for independently engaging the hooks, the loop of the strap including a portion from each hook being free of fixed connection with the plate.

3. In a device of the character described, a plate adapted to engage a corset, a plurality of hooks adapted to engage a corset, and a strap having one terminal secured to the plate, said strap being passed through the hooks in succession and in independent loop portions.

4. A lacing strap for a corset, comprising a terminal section and a plurality of end sections independently adjustable in length,

whereby the corset may be drawn up to conform to the body of the wearer by tension on the terminal section alone.

5. In a corset, the combination of a buckle, an apertured engaging plate and a lacing strap threaded through the buckle, carried over the plate, turned back and passed through the buckle to an engaging plate at the back edge section of the corset and carried thence forward to the said apertured engaging plate, substantially as shown and described.

6. In a corset, the combination of a lacing strap, a buckle thereon, a section of the lacing strap being carried in independent loops between the buckle and the back portion of the corset and the end sections of the lacing strap being brought together in engagement with the front section of the corset, substantially as shown and described.

Signed at Passaic, in the county of Passaic and State of New Jersey, this 28th day of October, A. D. 1915.

JULIA H. AUERBACH.
